UNITED STATES PATENT OFFICE

93,102

DESIGN FOR A NIPPLE PROTECTOR FOR NURSING BOTTLES OR SIMILAR ARTI- CLE

Dorman E. Hamiel, Columbus, Ohio, assignor of
one-half to Herbert C. Zelsman, Columbus,
Ohio

Application November 18, 1933, Serial No. 49,793

Term of patent 14 years

To all whom it may concern:

Be it known that I, DORMAN E. HAMIEL, a citizen
of the United States, residing at Columbus, in the
county of Franklin and State of Ohio, have in-
vented a new, original, and ornamental Design for
a Nipple Protector for Nursing Bottles or Similar
Article, of which the following is a specification,
reference being had to the accompanying drawing,
forming a part thereof.

Fig. 1 is a perspective view of a nipple protector
for nursing bottles or similar article, showing my
new design;

Fig. 2 is a vertical sectional view.

The dominant feature of my design is the bell-
shaped contour, relatively narrow at the top and
wide at the bottom flaring edge.

I claim:

The ornamental design for a nipple protector
for nursing bottles or similar article, as shown
and described.

DORMAN E. HAMIEL.
